SOUND RECORDING

George R. Groves, Burbank, Calif., assignor to
United Research Corporation, Burbank, Calif.,
a corporation of Delaware

Application February 10, 1936, Serial No. 63,079

4 Claims. (Cl. 179—100.3)

This invention relates to sound recording and reproduction, and particularly to the recording of the sound from a plurality of sources upon a single record in such a manner that these various sounds form a pleasing tone balance therebetween.

In the production of talking motion pictures wherein background sounds, such as music, noise of traffic, etc., are combined with the spoken dialogue, or other main sources of sound, it is necessary to maintain the proper volume level ratio between the dialogue and the background effects. If these sound effects are held too loud they mask the dialogue and tend to make it unintelligible, whereas when they are held too low, in an effort to make the dialogue intelligible, they are no longer life-like and the picture loses its realism.

One example of the difficulties encountered in producing the correct volume ratios between the background sound effects and the main sound or dialogue, would be a combining of the effects of a large crowd, such as at a prizefight, with the dialogue comprising the whispering or muttering of two boxers in the ring during a clinch. Their whisperings, for the purpose of story continuity, must be heard and understood by the audience, even though hundreds of people in the background are yelling and stamping their feet at the same time.

Usually the average volume level of the background sound would be held sufficiently low to prevent abnormally loud sounds, such as stamping of the feet, from drowning out or masking the dialogue at these points since this effect would distract the attention of the audience from the main sound or dialogue. However, in this case the lower sounds in the background effects are so low as to be unintelligible, if heard at all. Heretofore the dialogue and sound effects volume levels were generally controlled by an operator who manually adjusted the mixing panel in an effort to keep the same volume level ratio between the background sound and the dialogue. By the use of this arrangement it was impossible to constantly maintain an even balance between the sound effects and the dialogue due to the fact that the volume could not be controlled fast enough by hand to accurately follow the variations in the amplitude of the dialogue sound.

One object of the present invention is to combine dialogue and background effects while maintaining the abnormally loud background sounds below the dialogue level and at the same time allow the weaker background sounds to remain as high as possible. This is accomplished by

recording the background effects on a duping record while automatically compressing the volume range thereof during such recording. In the final step of the duping operation the compressed sound effects record is converted into corresponding electrical impulses and these impulses are combined with the uncompressed electrical impulses attained from, and corresponding to, the dialogue sound. The combined sound currents thus produced are fed into any suitable transducer such as a sound recorder for recording the sound currents upon a sound record. In co-pending application Serial No. 63,087 filed February 10, 1936, a method of and system for producing a similar final result with standard uncompressed sound effect records is disclosed and claimed.

By compressing the background sound currents the lower amplitude levels are increased in volume, and the higher amplitude levels are generally decreased in volume so as to produce a sound current in which the amplitude levels are maintained at substantially constant amplitude. An arrangement for so compressing the amplitude of the sound current impulses is disclosed and claimed in a co-pending application of Burton F. Miller, Serial No. 42,116, filed September 25, 1935.

For further details of this invention, references may be had to the accompanying drawing where- in:

Fig. 1 is a schematic view of a sound recording channel for producing a volume compression type of sound record.

Fig. 2 is a schematic view of a duping channel for duping two or more records upon a single final master record.

Fig. 3 is a circuit diagram of one form of compressor adapted to be employed in the compression recording channel illustrated in Fig. 1.

Referring in detail to Fig. 1, a microphone 10 converts the sound to be recorded into corresponding electrical impulses which are passed through an amplifier 11 and a manually adjustable potentiometer or attenuator 12. The amplified sound currents are passed through a volume compressor circuit 13, which will be described in detail hereafter, and are then photographically recorded as by means of a light valve 14 upon a sound record 15. The sound record 15 thus produced will therefore have a record of the sound recorded in microphone 10, but wherein the lower level sound representations are increased in amplitude to a greater degree than the higher level sound representations.

Fig. 2 shows the circuit for duping the compressed background sound effects and the uncompressed dialogue upon a single final record 16. In this apparatus the compressed sound effects record 15, as produced by the apparatus shown in Fig. 1, and an uncompressed dialogue record 28 as produced by any standard sound recording apparatus are placed in translating devices 18 and 19. Each of these translating devices comprises an exciter light 20, and lens and slit combination 21 for focusing a narrow horizontal beam of light upon the film to be reproduced. The beam of light thus modulated by the sound film record is allowed to fall upon a suitable photo-electric cell 23 or 29. The speech currents produced in the photo-electric cell 23 are passed through an amplifier 25, a potentiometer 26 and thence into a channel bus 27. The speech currents corresponding to the uncompressed dialogue sound film record 28 as generated in a photo-electric cell 29 are passed through an amplifier 30, a potentiometer 31 and are combined at 27 with the background sound currents from the film 15. The combined sound currents thus produced are passed through one or more suitable channel amplifiers 32, a channel potentiometer 33, and then into a suitable sound recorder for the film 16, such as a light valve 34. Preferably at this point the speech currents are passed through a noise reduction circuit 35 of the standard shuttering or biasing type in order to produce a variable area or variable density noise reduction sound track. However, the volume compression-expansion type of sound recording may be employed here by introducing a volume compressor circuit in the channel in place of the noise reduction circuit 35. In this case the duped record 16 would be of the compressed type and may be reproduced in sound reproducer employing a volume expansion circuit such as disclosed and claimed in the co-pending application of Burton F. Miller, above identified.

Referring to Fig. 3, which is a circuit diagram of a compressor circuit adapted to be employed in the recording channel of Fig. 1, the input 37 is coupled through an input transformer 38 to the grid-cathode circuit of a pair of impedance tubes 39 and 40. Tubes 39 and 40 are placed in series in a circuit between the input transformer 38 and an output transformer 41. A pair of leads 42 is shunted across the output of transformer 41 to feed a portion of the sound currents passing there-through, serially, through an amplifier 43, a rectifier 44 and a filter 45. The output terminals of filter 45 are connected in series in a common lead of the grid-cathode circuits of tubes 39 and 40. A static negative potential is applied to the grids of tubes 39 and 40 through the drop in potential across the resistance 46 provided in series with a direct current power supply, generally indicated at 48. It will thus be seen that a varying grid bias is provided by the rectified speech currents obtained through the pair of leads 42, which changes in accordance with the amplitude of the currents passing through the compressor circuit. The polarity of the output terminals of filter 45 is so arranged that at higher amplitude levels the negative grid bias is increased, thus increasing the impedance of tubes 39 and 40, thus decreasing the final output levels of these higher amplitudes.

In order to prevent the impedance of tubes 39 and 40 from becoming too high a resistance

50 of about 100,000 ohms, and a condenser 51 in series is shunted across the cathode-anode circuit of tube 39. A similar resistance 52 and condenser 53 in combination is shunted across the cathode-anode circuit of tube 40. In order to prevent the impedance of tubes 39 and 40 from dropping to an extremely low value a resistance 54 of about 100,000 ohms is provided in series 5 in the grid-cathode circuits of tubes 39 and 40. By the use of resistance 54 any tendency for the 10 grids of tubes 39 and 40 to be driven positive by high signal levels will be counteracted by the drop in potential across this resistance 54 due to the grid current flow.

Although the above description and accompanying drawing have described and illustrated the invention in conjunction with the sound-on-film type of sound record, it is to be understood that any type of sound record may be employed such as wax, wire, etc., without departing from 15 the scope of the invention.

Having thus described the invention, what is claimed as new and desired to be secured by Letters Patent is:

1. The method of producing a standard noise 25 reduction record of a primary sound and of a secondary sound comprising translating the primary sound into a sound record having variations in amplitude directly proportional to the variations in amplitude of said source, translating said secondary sound into a sound record in which the amplitudes have been varied in accordance with a predetermined ratio, simultaneously translating said records into sound currents varying in accordance with the records, 30 combining said currents into a common duping channel while varying the relative amplitudes therebetween so that higher level amplitudes of said secondary sound do not interfere with said primary sound amplitudes, while maintaining 35 said low level sounds at an amplitude to maintain a high sound to noise ratio, and recording said currents into a standard noise reduction record.

2. The method of producing a sound print having 45 background sound effects and dialogue therein comprising translating said dialogue sounds into a sound record in which the amplitudes of said record are proportional to the amplitudes of said dialogue sounds, translating the background sound effects into a record thereof in which the amplitudes are not proportional to the original amplitudes but vary in a predetermined ratio, simultaneously translating each of said records into corresponding electrical currents, 50 combining said electrical currents in a common duping channel, and adjusting the amplitude levels of each of said currents before their combination, said adjustment being such that the higher amplitudes of said sound effects do not 55 interfere with said dialogue sounds, and recording said combined currents into a standard noise reduction record.

3. The method of producing a sound print in 65 accordance with claim 2, in which the translation of said background effects into a record comprises reducing the higher level amplitudes to a larger extent than the lower level amplitudes.

4. The art of producing a combination sound 70 print of dialogue sounds occurring at different times than background sounds to be combined therewith comprising recording said dialogue sounds in a normal manner to maintain the same variation in amplitude on the record as the vari- 75

ation in amplitude of the original dialogue, recording the sound effects while compressing said sound effects to vary the larger amplitudes to a greater degree than the smaller amplitudes, simultaneously translating both of said records into electrical currents and combining said cur-

rents in a common duping channel, the amplitudes of said currents before their combination being adjusted to maintain a predetermined relationship between the high and low amplitudes thereof.
